US00D497177S1

(12) United States Design Patent (10) Patent No.: **US D497,177 S**
Matsumoto et al. (45) Date of Patent: **** Oct. 12, 2004**

(54) TAPE PRINTING MACHINE

(75) Inventors: **Shigeru Matsumoto**, Toyokawa (JP);
Kazuyoshi Minaminaka, Suzuka (JP);
Susumu Murata, Nagoya (JP); **Shin Manabe**, Nagoya (JP)

(73) Assignee: **Brother Industries, Limited**, Nagoya (JP)

(**) Term: **14 Years**

(21) Appl. No.: **29/195,502**

(22) Filed: **Dec. 15, 2003**

(30) Foreign Application Priority Data

Jun. 26, 2003 (JP) 2003-018241

(57) CLAIM

The ornamental design for tape printing machine, as shown and described.

DESCRIPTION

FIG. 1 is a perspective view of a tape printing machine showing our new design;

FIG. 2 is a front view thereof;

FIG. 3 is a rear view thereof;

FIG. 4 is a right-side view thereof; and,

FIG. 5 is a bottom view thereof.

The broken lines are for illustrative purposes only and do not form part of the claimed design.
